VALVE GRINDING MACHINE

Carl G. Flygare, Worcester, Mass., assignor to Norton Company, Worcester, Mass., a corporation of Massachusetts

Application November 29, 1954, Serial No. 471,682

10 Claims. (Cl. 51—3)

This invention relates to grinding machine, and more particularly to a valve grinding machine.

One object of the invention is to provide a simple and thoroughly practical valve grinding machine. Another object is to provide a grinding machine having a shaped grinding wheel which is arranged so that an axial feeding movement of the grinding wheel serves to grind a frusto-conical face on the valve being ground. Another object is to provide a grinding machine having a grinding wheel provided with a frusto-conical and an adjacent cylindrical face whereby an axial feeding movement of the grinding wheel serves to grind a frusto-conical face on the valve being ground. Another object of the invention is to provide a grinding wheel having a taper and a cylindrical face which is arranged so that an axial feeding movement of the grinding wheel serves to grind a cylindrical face on a valve being ground. Another object is to provide a grinding machine having a shaped grinding wheel which is arranged so that an axial feeding movement of the grinding wheel serves to grind a cylindrical face on the valve after which a swivelling movement of the grinding wheel serves to grind a bevelled face adjacent to the cylindrical portion on the valve. Another object is to provide a grinding machine having a pair of grinding wheels arranged on opposite sides of a valve to be ground both of which are shaped so that a simultaneous axial feeding movement of the wheels serves to grind a frusto-conical valve face and an adjacent cylindrical face thereon after which a swivelling movement of one of the wheels serves to grind a bevelled face adjacent to the cylindrical face. Another object is to provide means actuated by and in timed relation with the axial feeding movement of one of the grinding wheels automatically to initiate a swivelling movement thereof so that the cylindrical face is first ground after which the wheel swivels automatically to grind an adjacent bevelled face. Other objects will be in part obvious or in part pointed out hereinafter.

In the accompanying drawings in which is shown one of various possible embodiments of the mechanical features of the invention,

Fig. 1 is a plan view of the improved valve grinding machine,

Fig. 2 is a side elevation of the machine,

Fig. 3 is a fragmentary vertical sectional view, on an enlarged scale, taken approximately on the line 3—3 of Fig. 1, through one of the grinding wheel slides;

Fig. 4 is a fragmentary vertical sectional view, taken approximately on the line 4—4 of Fig. 3;

Fig. 5 is a fragmentary horizontal view, on an enlarged scale, taken approximately on the line 5—5 of Fig. 2, through one of the wheel feeding mechanisms;

Fig. 6 is a fragmentary vertical sectional view, on an enlarged scale, taken approximately on the line 6—6 of Fig. 1, through the work supporting spindle;

Fig. 7 is a fragmentary vertical sectional view, on an enlarged scale, taken approximately on the line 7—7 of

2

Fig. 2, through the work head traversing and positioning mechanism;

Fig. 8 is a diagrammatic view showing the relative positions of the grinding wheels and the faces of the work piece to be ground; and

Fig. 9 is a combined electric and hydraulic diagram of the actuating and control mechanisms of the machine.

A valve grinding machine has been illustrated in the drawings for simultaneously grinding a plurality of faces on an automotive engine valve. As illustrated diagrammatically in Fig. 8 a valve 10 is mounted in a work supporting chuck to be hereinafter described and the frusto-conical face 11, a cylindrical face 12 and a conical face 13 are ground in a single machine. A grinding wheel 14 is provided with a slightly conical face 15 adjacent to a cylindrical face 16 which are shaped and arranged so that when the grinding wheel 14 is moved in an axial direction, the frusto-conical face 15 will engage and grind the frusto-conical face 11 of the valve 10 until the cylindrical face 16 of the wheel 14 moves into engagement with the frusto-conical face 11 at which time the face is ground to the desired and predetermined extent. At the same time a single grinding wheel 17 which is arranged diametrically opposite to the grinding wheel 14 is provided with a conical face 18 adjacent to a cylindrical face 19 so that when the grinding wheel 17 is fed in an axial direction toward the left, the face 18 engages and grinds the cylindrical face 12 of the valve 10. This grinding continues until the cylindrical face 19 of the grinding wheel 17 traverses across the cylindrical face 12 of the valve 10 to finish grind the face 12 to the desired and predetermined extent. The continued movement of the wheel 17 toward the left causes a frusto-conical face 20 of the wheel 17 to move into operative relationship with the face 13 of the valve 10 at which time the axis of the grinding wheel 17 is swivelled in a horizontal plane so that frusto-conical face 20 moves into engagement with the face 13 of the valve to start grinding thereon. This latter grinding continues until a face 21 of the grinding wheel 17 swings into grinding engagement with the face 13 to finish grind the same to the desired and predetermined extent.

The valve grinding machine comprises a base 30 which supports a pair of angularly arranged wheel slides 31 and 32 which are arranged rotatably to support the grinding wheels 14 and 17. The wheel slides 31 and 32 are substantially identical in construction, consequently only one of these slides has been illustrated in detail. The wheel slide 32 (Fig. 3) is supported by a V-way 35 and a flat-way 36 formed on the upper surface of a wheel slide base 85 on the base 30. The wheel slide 32 is provided with a pair of spaced spindle bearings 37 and 38 which rotatably support a grinding wheel spindle 39. The left hand end of the spindle 39 is provided with a wheel mounting 40 for supporting the grinding wheel 17. The grinding wheel 17 is partially surrounded by a conventional type wheel guard 41. A multiple V-groove pulley 42 is mounted on the right hand end of the wheel spindle 39 and is drivingly connected by multiple V-belts 43 with a multiple V-groove pulley (not shown) contained within a belt guard 44 which is mounted on a motor shaft 45 of a driving motor 46. The motor 46 is adjustably mounted on the upper surface of the wheel slide 32.

A suitable feeding mechanism is provided for adjusting the wheel slide 32 to position the operative faces of the grinding wheel 17 into the desired relationship with the work piece being ground. This mechanism may comprise a manually operable feed wheel 50 which is operatively connected to rotate a gear 51 (Fig. 2) mounted on the right hand end of a rotatable shaft 52. The left hand end of the shaft 52 is provided with a bevel gear 53 which meshes with a bevel gear 54 which is rotatably journaled

within the wheel slide base 85 of the machine and is slidably keyed to a cylindrical portion 55 of a rotatable feed screw 56. The feed screw 56 meshes with or engages a half-nut 57 depending from the underside of the wheel slide 32. It will be readily apparent from the foregoing disclosure that a rotary motion of the feed wheel 50 will be imparted through the mechanism above described to cause a transverse movement of the wheel slide 32, that is, in a direction normal to the axis of the wheel spindle 39. This feeding mechanism is utilized in the present machine merely for positioning the grinding wheel 17 and for compensating for wheel wear thereon.

The axial grinding feed of the wheel 17 for grinding the cylindrical face 12 of the valve 10 is accomplished by an axial movement of the grinding wheel spindle 39.

A hydraulically operated mechanism is provided for axially moving the spindle 39 which preferably comprises a cylinder 60 (Fig. 3) which contains a slidably mounted piston 61 fixedly mounted on the right hand end of a piston rod 62. The piston rod 62 is operatively connected to a vertically arranged stud 63 carried by a rock arm 64. The rock arm 64 is pivotally supported by a shaft 65 within the wheel slide 32. The rock arm 64 is provided with a yoked-shaped portion having a pair of diametrically arranged studs 66 and 67 which engage apertures in a thrust ring 68 which rides between a thrust surface 69 and a thrust collar 70 carried by the wheel spindle 39 (Fig. 3).

When fluid under pressure is passed through a pipe 71 into a cylinder chamber 72, the piston 61 will be moved toward the left to rock the rock arm 64 in a clockwise direction to axially move the wheel spindle 39 toward the left so that faces 18 and 19 of the grinding wheel 17 will grind the cylindrical face 12 of the valve 10 to the desired and predetermined extent. During this movement of the piston 61, fluid within a cylinder chamber 73 may exhaust through a pipe 74, through a throttle valve 75 which controls the rate of movement of the piston 61 toward the left (Fig. 9). A throttle valve 76 is provided in the pipe line 71 which serves to control the rate of flow of fluid through the pipe 71 when passed to or exhausted from the cylinder chamber 72. A check valve 77 is provided in the pipe line 74 which is arranged so that fluid passing through a pipe 78 into the cylinder chamber 73 may by-pass the throttle valve 75 and thereby move the piston 61 toward the right at a rate controlled by the throttle valve 76.

The movement of the wheel spindle 39 toward the left continues until the face 19 of the grinding wheel 17 has ground the cylindrical face 12 of the valve 10 to the desired and predetermined extent at which time the stud 63 engages an adjustably mounted stop screw 80 which is supported by a boss 81 projecting upwardly from the wheel slide 32. The piston rod 62 is provided with a head portion 82 which is operatively connected by an elongated slot 82a with the upper end of the stud 63. The head 82 is provided with an upwardly projecting bracket 83 carrying an adjustably mounted stop screw 84 which is arranged to engage the actuating plunger of a normally closed limit switch LS1.

A swivelling mechanism is provided for swivelling the axis of the wheel spindle 39 in a horizontal plane so that the operative faces 20 and 21 on the grinding wheel 17 will grind the frusto-conical face 13 on the valve 10. The wheel slide 32 is preferably supported on a wheel slide base 85 which is arranged to swivel about the axis of a stud 85a on the machine base 30 (Fig. 1). A hydraulically operated mechanism is provided for swivelling the wheel slide base 85 comprising a cylinder 86 containing a slidably mounted piston 87. The cylinder 86 is fixedly mounted on the base 30. The piston 87 is operatively connected to a piston rod 88, the left hand end of which is connected by a stud 89 with a pair of spaced links 90. The links 90 are connected by a stud 91 with a bracket 92 which is fixedly mounted on the rear of the wheel slide base 85. An adjustably mounted stop screw 93 carried

by a bracket 94 fastened to the base 30 of the machine serves to limit the movement of the piston 87 toward the left.

The piston rod 88 extends toward the right and is arranged in the path of an adjustably mounted stop screw 95 carried by a bracket 96 fastened to the base 30 of the machine. A piston type control valve 97 is provided for controlling the admission to and exhaust of fluid from the cylinder 86. The valve 97 is normally held in a left hand end position by a compression spring 98. A solenoid S1 is provided for shifting the valve 97 toward the right into a reverse position. In the position of the valve 97 (Fig. 9), fluid under pressure passing through a pipe 99 passes through a throttle valve 100 and also through a check valve 101, through a pipe 102 into the cylinder chamber 103 to move the piston 87 toward the left to shift the bracket 92 into engagement with the stop screw 93 to maintain the wheel slide in a normal position with the axis of the wheel spindle 39 substantially parallel to the axis of the work piece being ground. During this movement of the piston 87 toward the left fluid within a cylinder chamber 104 may exhaust through a pipe 105, through a throttle valve 106 and through a pipe 107. A check valve 108 is provided between the pipes 105 and 107 so that when fluid under pressure is passed through the pipe 107, it may by-pass through the throttle valve 106 and also through the check valve 108. During this movement, the throttle valve 100 will control the rate of movement of the piston 87 toward the right. The throttle valve 106 serves to control the rate of movement of the piston 87 toward the left. It will be readily apparent from the foregoing disclosure that by manipulation of the throttle valves 100 and 106 the rate of movement of the swivelling of the wheel slide base 85 may be independently controlled in both directions.

As illustrated in Fig. 9, the valve 97 is shown in a position with the grinding wheel 17 positioned for grinding the cylindrical face 12 on the valve 10. During the movement of the wheel spindle 39 toward the left, as it approaches the left hand end of its stroke, the stop screw 84 engages the actuating plunger of the limit switch LS1 to close the contacts therein so as to energize the solenoid S1 thereby shifting the valve 97 toward the right so that fluid under pressure will be passed through the pipe 107, through the throttle valve 106 and the check valve 108, through the pipe 105 into the cylinder chamber 104 to move the piston 87 toward the right thereby swivelling the wheel slide base 85 in a counter-clockwise direction to shift the grinding wheel 17 from the full line position (Fig. 8) into the broken line position 17a, during which movement the operative faces 20 and 21 on the grinding wheel 17 will grind the frusto-conical face 13 to the desired and predetermined extent. The swivelling movement of the wheel slide base in a counter-clockwise direction continues until the piston rod 88 engages the stop screw 95.

A fluid pressure system is provided for supplying fluid under pressure to the various mechanisms of the machine comprising a motor driven fluid pump 110 which draws fluid through a pipe 111 from a reservoir 112 and passes fluid under pressure through a pipe 113 to the various mechanisms of the machine. A pressure relief valve 114 is provided in the pipe line 113 to facilitate by-passing excess fluid under pressure to the reservoir 112 so as to maintain the desired operating pressure within the system.

The wheel slide 31 is similarly supported on a V-way and a flat way (not shown) formed on the upper surface of a wheel slide base 122 which is fixedly mounted on the base 30 of the machine. The wheel slide 31 is provided with a rotatable wheel spindle 123 for supporting the grinding wheel 14. The spindle 123 is driven by an electric motor 124 mounted on the upper surface of the wheel slide 31. A belt drive the same as that described in connection with wheel slide 32 is provided within a belt guard 125 (Fig. 1) to transmit power from the motor 124 to the wheel spindle 123.

A feeding mechanism is provided for the wheel slide 31 which is identical in construction to that previously described in connection with the wheel slide 32 and comprising a manually operable feed wheel 126 which is connected to rotate a gear 127 carried by a rotatable shaft 128. The shaft 128 is provided with a bevel gear 129 which meshes with a bevel gear 130 which is operatively connected to rotate a feed screw 131. The feed screw 131 meshes with a half-nut 132 depending from the underside of the wheel slide 31. It will be readily apparent from the foregoing disclosure that manual actuation of said wheel 126 will be transmitted through the mechanism just described to adjust the position of the wheel slide 31 relative to the base 30. This mechanism is utilized in the present case merely for the purpose of 15 positioning the wheel 14 in setting up the machine and to facilitate compensation for wheel wear.

A hydraulically operated mechanism is provided for moving the wheel spindle 123 axially to impart a grinding feed to the wheel 14 so that the tapered face 15 first grinds the face 11 of the valve 10 after which the face 16 completes the grinding to the desired size. This hydraulically operated mechanism comprises a cylinder 135 which contains a slidably mounted piston 136. The piston 136 is connected to the left hand end of a piston rod 137 (Fig. 9). The piston rod 137 is provided with a head 138 at its right hand end having a transversely extending slot 139 which straddles a stud 140. The stud 140 is mounted on a rock arm 141 which is pivotally supported by a stud 142 within the wheel slide 31. The rock arm 141 is provided with a yoked portion having diametrically opposed studs 143 to operatively connect the arm 141 to a thrust collar 144 by means of which the swinging movement of the arm 141 may be transmitted to produce an axial feeding movement of the wheel spindle 123. An adjustably mounted stop screw 145 carried by an upwardly projecting boss 146 on the wheel slide 31 is arranged to engage the right hand end face of the head 138 positively to limit the movement of the piston 136 toward the right. When fluid under pressure is passed 40 through the pipe 78, it may pass through a throttle valve 147 and also through a check valve 148 into a cylinder chamber 149 to move the piston 136 together with the wheel spindle 123 toward the left into an initial position. During movement of the piston 136 toward the left fluid within a cylinder chamber 150 may exhaust through a pipe 151, through a throttle valve 152 into the pipe 71. The valve 152 serves to control the exhaust of fluid from the cylinder chamber 150 and thereby to control 45 the rate of movement of the piston 136 toward the left.

When it is desired to start a grinding feed of the wheel 14, fluid under pressure is passed through the pipe 151 into the cylinder chamber 150 to cause the piston 136 to move toward the right thereby imparting an axial movement to the wheel spindle 123 toward the right so that the frusto-conical face 15 of the wheel moves into grinding engagement with face 11 which continues until the cylindrical face 16 moves into engagement with the face 11 of the valve 10 to grind the same to the desired and predetermined extent. During this movement of the piston 136 toward the right fluid within the cylinder chamber 149 may exhaust through a pipe 153, through the throttle valve 147 into the pipe 78. In this case the check valve 148 closes and the throttle valve 147 controls the rate of axial grinding feed of the wheel spindle 123.

A piston type control valve 160 is provided for simultaneously controlling the passage of fluid to and exhaust of fluid from the cylinders 60 and 135. The valve 160 is normally held in a right hand end position by a compression spring 162. A solenoid S2 is provided which when energized serves to shift the control valve to the left thereby reversing the flow of fluid under pressure to the cylinders 60 and 135.

A longitudinally movable work supporting carriage 170 is mounted on a dove-tailed slideway 171 formed on the 75

upper surface of the base 30. A manually operable traversing mechanism is provided for the carriage 170 comprising a hand wheel 172 mounted on the left hand end of a rotatable shaft 173 (Fig. 7). The right hand end of the shaft 173 is provided with a gear 174 which meshes with a rack bar 175 depending from the underside of the carriage 170.

The carriage 170 serves as a support for a rotatable work spindle 176 (Fig. 6) which is supported by a pair of spaced anti-friction bearings 177 and 178. An electric motor 180 supported on the carriage 170 is connected by a belt drive 181 with a back shaft 182 having a pulley 183 which is connected by a V-belt 184 with a pulley 185 keyed onto the spindle 176.

A work receiving collet or chuck is provided at the right hand end of the work spindle 176 for supporting a valve 10 to be ground. This work collet is a standard commercial collet, consequently it will not be described in detail. The collet 190 is connected by an actuating rod 191 with a hydraulically operated actuating mechanism. This mechanism comprises a piston 192 mounted on the left hand end of the rod 191. The piston 192 is contained within a cylinder 193. The cylinder 193 is fixedly mounted on a collar 187 which is keyed onto the left hand end of the work spindle 176 so that the cylinder 193 together with the piston 192 rotate with the spindle 176.

A non-rotatable housing 188 is supported by a cylindrical member 189 which is fixedly mounted relative 30 to the left hand end cylinder cap of the cylinder 193. The member 189 is provided to facilitate conveying fluid under pressure to and exhaust from the cylinder 193. When fluid is passed under pressure through a pipe 196, it passes through a passage 197 into a cylinder chamber 198 to move the piston 192 toward the left so as to actuate the collet 190 to clamp a valve to be ground therein. During this movement, fluid within a cylinder chamber 199 passes through a passage 200 into an annular groove 201 and out through a pipe 202. A drain pipe 203 is provided for draining fluid from the chamber 204.

A rotary type control valve 205 is provided for controlling the admission to and exhaust of fluid from the cylinder 193. The valve 205 is provided with a valve 45 rotor 206 which is actuated by a manually operable lever 207. In the position of the valve 205 (Fig. 9) fluid from the pressure pipe 113 passes into a valve chamber 209, through the pipe 196, through the passage 197 into the cylinder chamber 198 to clamp the work receiving collet. During this clamping movement fluid within the cylinder chamber 199 may exhaust through the passage 200, the annular groove 201, through the pipe 202, into a valve chamber 210, through a valve passage 211, through a valve chamber 212 and exhausts through the pipe 203 into the reservoir 112.

The control lever 207 of the valve 205 is provided with an arm 215 which is arranged so that when the control lever is shifted in a counter-clockwise direction into the full line position illustrated in Fig. 9, the arm 215 will engage the actuating plunger of a limit switch LS2 to close the normally open contacts therein and to thereby close an electric circuit. A selector switch 216 is provided to allow actuation of the machine without other electrical controls by shifting the control lever 207 in a counter-clockwise direction into the full line position (Fig. 9).

The operation of the valve grinding machine will be readily apparent from the foregoing disclosure. When it is desired to start a grinding cycle, a valve 10 to be ground is placed in the collet chuck 190. A control lever 207 is then shifted from the broken line position 70 207a (Fig. 9) in a counter-clockwise direction into the full line position 207 to clamp the valve 10 within the collet 190. The arm 215 on the control lever swings to close the normally open limit switch LS2. A cycle start switch 220 is then closed to energize an electric timer

221 which is arranged to control the grinding cycle. The timer 221 may be any of the well known commercial varieties such as for example the Microflex electric timer manufactured by the Signal Electric Corp. of Moline, Illinois. The energizing of the timer 221 serves to energize the solenoid S2 to shift the valve 160 toward the left so that fluid under pressure is simultaneously passed to the cylinders 60 and 135 to start an axial movement of the grinding wheel 14 toward the right and the grinding wheel 17 toward the left simultaneously to grind the frusto-conical valve face 11 and the cylindrical face 12 in a manner above described. The movement of the grinding wheel 14 toward the right continues until the stud 140 engages the stop screw 145 which serves to positively limit the infeed thereon. Similarly the feeding movement of the grinding wheel 17 toward the left continues until the stud 63 engages the stop screw 80 positively to limit the feeding movement of the grinding wheel 17.

At the same time the stud 63 engages the stop screw 80, the stop screw 84 actuates and closes the limit switch LS1 which energizes the solenoid S1 to shift the valve 97 toward the right so as to pass fluid under pressure to the cylinder 86 to start a swivelling movement of the wheel slide base 85 in a counter-clockwise direction so that the faces 20 and 21 on the grinding wheel 17 will grind the bevel face 13 of the valve 10 to the desired and predetermined extent. The swivelling movement of the wheel slide base 85 continues until the right hand end of the piston rod 88 engages a stop screw 95 positively to limit the swivelling of the grinding wheel 17.

When the timer times out, the solenoids S1 and S2 are deenergized so that the valve 160 returns to the position illustrated in Fig. 9 to return the grinding wheels 14 and 17 to their initial positions as illustrated in Fig. 8. At the same time deenergizing the solenoid S1 shifts the valve 97 into the position illustrated in Fig. 9 to swivel the wheel slide base 85 in a clockwise direction into its initial position. The ground valve may then be released from the collet 190 by shifting the control lever 207 in a clockwise direction into position 207a. The ground valve may then be removed and a new valve to be ground inserted in the collet chuck 190.

A stop switch 222 is provided to facilitate stopping the grinding cycle at any time during the grinding operation if desired. Actuation of the stop switch 222 will serve to deenergize the timer 221 thereby deenergizing the solenoids S1 and S2 to immediately return the grinding wheels to their initial positions as illustrated in Fig. 8.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth, or shown in the accompanying drawings is to be interpreted as illustrative, and not in a limiting sense.

I claim:

1. In a valve grinding machine having a base, a rotatable work supporting spindle for supporting a valve to be ground, a transversely movable wheel head on said base, a rotatable grinding wheel spindle thereon, spaced bearings on said head to support said spindle, said spindle being arranged for an axial movement within said bearings, a grinding wheel on said spindle, the axis of said spindle being arranged parallel to an element of the finish ground work piece, an operative face on said grinding wheel which is shaped so that a portion of the operative element of said wheel face is at an acute angle to and the remainder of said wheel element is aligned with an element of the surface to be ground, means operatively connected to impart an axial feeding movement to the wheel spindle so that the first portion of said wheel face grinds the work piece to approximately the desired extent after which the second portion of said face finish grinds the work piece, and means to stop the axial feeding movement of the wheel spindle when the work piece has been ground to a predetermined size.

5

2. In a valve grinding machine as claimed in claim 1, in combination with the parts and features therein specified of means to adjust said wheel head transversely to facilitate compensation for wheel wear and wherein said stop means comprises an adjustable stop.

10

3. In a valve grinding machine having a base, a rotatable work supporting spindle for supporting a valve to be ground, a transversely movable wheel head on said base, a rotatable grinding wheel spindle, spaced bearings

15

on said head to support said spindle, said spindle being arranged for an axial movement within said bearings, a grinding wheel on said spindle, the axis of said spindle being arranged parallel to an element of the finish ground work piece, an operative face on said grinding wheel

20

which is shaped so that a portion of the operative element of said wheel face is at an acute angle to and the remainder of said wheel element is aligned with an element of the surface to be ground, means including a piston and cylinder operatively connected to impart an axial

25

feeding movement to said wheel spindle so that the first portion of said wheel face grinds the work piece and the second portion of said face sizes the work piece, and means to stop the axial feeding movement of the wheel spindle when the work piece has been ground to the

30

desired extent.

35

4. In a grinding machine having a base, a transversely movable wheel head thereon, swivel support for said head for swivelling said head in a horizontal plane relative to the base, a rotatable wheel spindle on said head, spaced bearings on said head to support said spindle, said spindle being arranged for an axial movement within said bearings, a grinding wheel on said spindle having a frusto-conical and an adjacent cylindrical face to facilitate grinding a surface on the work piece when the wheel spindle is moved in an axial direction, means to feed said spindle axially to grind said surface to the desired and predetermined extent, a second portion of the operative face of the grinding wheel having a pair of adjacent frusto-conical portions, and means to swivel said head in a horizontal plane after one portion of the work piece has been ground so that the adjacent frusto-conical faces of the wheel swings into engagement with a second portion of the work piece to grind the same to the desired and predetermined extent.

40

5. In a grinding machine as claimed in claim 4 in combination with the parts and features therein specified of a piston and cylinder mechanism operatively connected to move said spindle axially within its bearings, and an adjustable stop to limit said axial feeding movement when the work piece has been ground to the desired and predetermined extent.

45

6. In a grinding machine as claimed in claim 4, in combination with the parts and features therein specified of a piston and cylinder mechanism operatively connected to cause an axial feeding movement of the grinding wheel

50

spindle to grind a portion of the work piece to the desired and predetermined extent, an adjustable stop to limit said axial feeding movement, means including a piston and cylinder mechanism operatively connected to swivel said wheel head, a solenoid actuated control valve therefor, and a limit switch actuated in timed relation with the axial feeding movement of the grinding wheel to initiate a swivelling movement of the wheel head after the first surface has been ground to the desired and predetermined extent to grind a second surface on the work piece.

55

7. In a valve grinding machine having a base, a rotatable work support spindle for supporting a valve to be ground, a pair of angularly disposed transversely movable wheel heads on said base arranged on opposite sides of the work spindle, a rotatable grinding wheel spindle

60

70

75

on each of said heads, spaced spindle bearings on each head to support said spindles, said spindles being arranged for an axial movement within said bearings, a grinding wheel on each of said spindles, the axis of each of said spindles being arranged parallel to spaced elements of the finish ground work piece, an operative face on each of said grinding wheels which is shaped so that a portion of the operative element of each of said faces is at an acute angle to and the remainder of the said element is aligned with an element of the surface to be ground simultaneously to grind adjacent portions on a work piece, and means on each of said wheel heads to impart an axial feeding movement to said spindles so that the first portion of each of said wheel faces rough grinds a surface on the work piece and the second portion on each of said faces finish grinds the work piece to the desired and predetermined extent.

8. In a valve grinding machine having a base, a rotatable work supporting spindle for supporting a valve to be ground, a pair of angularly disposed transversely movable wheel heads on said base arranged on opposite sides of the work spindle, a rotatable grinding wheel spindle on each of said heads, spaced spindle bearings on each head to support said spindles, said spindles being arranged for an axial movement within said bearings, a grinding wheel on each of said spindles, the axis of each of said spindles being arranged parallel to spaced elements of the finish ground work piece, an operative face on each of said grinding wheels which is shaped so that a portion of the operative element of each of said faces is at an acute angle to and the remainder of the said element is aligned with an element of the surface to be ground simultaneously to grind adjacent portions on a work piece, means including a piston and cylinder on each of said wheel heads to impart an axial feeding movement to said spindles so that the first portion of each of said wheel faces grinds a surface on the work piece and the second portion on each of said faces sizes the work piece to the desired extent, and means including a solenoid actuated control valve simultaneously to control the admission to

and exhaust of fluid from each of said cylinders so as to impart a simultaneous axial feeding movement to each of said spindles to facilitate simultaneously grinding adjacent portions on a work piece.

5 9. In a grinding machine as claimed in claim 8, in combination with the parts and features therein specified of means including an independent piston and cylinder to swivel one of said heads in a horizontal plane, a pair of adjacent frusto-conical faces on the grinding wheel on said latter head, a control valve therefor, and means actuated by and in timed relation with the axial movement of said spindle on the head that swivels to initiate a swivelling movement of said head to grind an adjacent third face on the work piece being ground.

10 10. In a grinding machine as claimed in claim 8, in combination with the parts and features therein specified of an electric time delay relay to control said solenoid-actuated valve so as to control the duration of the grinding operation, means including an independent piston and cylinder to swivel one of said heads in a horizontal plane, a pair of adjacent frusto-conical faces on the grinding wheel on said latter head, a solenoid-actuated control valve to control the admission to and exhaust of fluid from said latter cylinder, and means including a limit switch actuated by and in timed relation with the axial movement of said spindle to initiate a swivelling movement of said head to grind an adjacent third face on the work piece being ground.
